UNITED STATES PATENT OFFICE.

RANDOLPH A. WINTERS, OF ATWOOD, KANSAS.

FENCE-WIRE TIGHTENER.

SPECIFICATION forming part of Letters Patent No. 729,910, dated June 2, 1903.

Application filed June 12, 1902. Serial No. 111,394. (No model.)

To all whom it may concern:

Be it known that I, RANDOLPH A. WINTERS, a citizen of the United States, residing at Atwood, county of Rawlins, and State of Kansas, have invented certain new and useful Improvements in Fence-Wire Tighteners, of which the following is a specification.

My invention relates to fence-wire tighteners, and is designed as an improvement on the fence-wire tightener, particularly the chuck, set forth in United States Letters Patent No. 696,291, granted to me March 25, 1902.

The object of the present invention is the provision of an improved and novel chuck or holding device for the staple which is used to take up slack in the fence-wire, my aim being to simplify the chuck and render it cheaper to manufacture and at the same time provide a chuck which may be quickly and easily opened and closed.

Having the foregoing object in view, the invention consists of certain improved features and novel combinations of parts set forth in detail hereinafter and recited in the appended claims.

In the accompanying drawings, Figure 1 is a view illustrating the initial position of the staple and the tool; Fig. 2, a view showing the position of the tool and illustrating the bend formed after the tool has completed its work; Fig. 3, a detail of the bend formed in the fence-wire; Figs. 4 and 5, details of the improved chuck constituting the present invention; Fig. 6, a detail view of the chuck before connection to the handle.

The tool on which the present invention is used has a handle 1, with a right-angular arm 2 formed integral therewith provided with a hooked end 3.

The numerals 4 and 5 designate twin jaws having flat tapered ends 6 wedged in a rectangular opening 7 in the handle 1 and secured together by the rivet or fastening 8. The inner faces 6' of the ends 6 diverge, as shown in Fig. 6, and when the ends 6 are wedged into the opening 7 the faces 6' are pressed together, as shown in Fig. 4. This manner of tapering the jaws and securing them gives their heads or free ends a tendency to spring apart to a limited degree, due also to the inherent resiliency of the metal of which they are made. The heads of the jaws

are provided on their inner and adjacent faces with parallel grooves 9 and 10, spaced apart sufficiently to properly receive the legs of the 55 staple 11, which is used to tighten the wire. In one jaw is provided a square hole 12 and in the other jaw a round hole 13. A threaded bolt 14 passes through these holes, being provided with a head 15 at one end, a squared 60 portion 16 received in the square hole 12 to prevent turning, and has a wing-nut 17 on its screw-threaded end, whereby the jaws may be clamped on the staple inserted in the grooves to hold the staples securely while the 65 wire is being tightened.

In using the invention when it is desired to take up the slack in fence-wires a staple 11 is made to straddle the fence-wire, as shown in Fig. 1. Its legs are inserted in the 70 grooves of the jaws and the jaws clamped thereon. The handle is then given a three-quarters turn toward the right and the hooked end on the arm brought under the fence-wire, whereupon it will be as shown in Fig. 2. 75 This engagement of the hooked end of the arm with the wire holds the tool rigid, and a binding-wire 18 is then slipped through the closed end of the staple and its ends twisted a few times around the fence-wire on opposite 80 sides of the staple. The tool can then be removed, and the joint or bend formed will remain permanent.

Having thus described my invention, what I claim as new, and desire to secure by Letters 85 Patent, is—

1. In a fence-wire tightener, the combination with a handle having an opening, of a chuck comprising jaws provided with wedge shape or tapered ends fitted tightly in the 90 opening, whereby their free ends spread apart of their own tendency, and a clamping device for closing the free portions of the jaws.

2. In a fence-wire tightener, the combination with a handle having an opening, of a 95 chuck comprising jaws provided with flattened wedge shape or tapered portions fitted tightly in the opening in the handle, whereby their free ends spread apart of their own tendency, a fastener connecting the jaws together adjacent their point of fastening to the handle, and a clamping device for closing the free portions of the jaws.

3. In a fence-wire tightener, the combina-

tion with a handle having an opening, of a
5 chuck comprising resilient or springy jaws
provided with flattened wedge shape or
tapered ends fitted tightly in the opening in
the handle, whereby the free ends of the jaws
have a tendency to spread apart, said jaws
at their free ends being provided with matching
pairs of grooves, a screw-threaded bolt
passing through the free ends of the jaws

and having a squared portion fitting a simi- 10
lar opening in the jaw, and a clamping-nut
on the bolt.

In testimony whereof I hereunto affix my
signature in presence of two witnesses.

RANDOLPH A. WINTERS.
